UNITED STATES PATENT OFFICE.

JOSEPH J. BUSER, OF FREEDOM, PENNSYLVANIA.

CLOTHES-LINE REEL.

1,077,245.

Specification of Letters Patent.

Patented Oct. 28, 1913.

Application filed February 24, 1913. Serial No. 750,346.

To all whom it may concern:

Be it known that I, JOSEPH J. BUSER, a citizen of the United States of America, residing at Freedom, in the county of Beaver 5 and State of Pennsylvania, have invented certain new and useful Improvements in Clothes-Line Reels, of which the following is a specification, reference being had thereto in the accompanying drawing.

10 This invention relates to clothes line reels, and the primary object of my invention is to provide a hand reel of novel construction that permits of a clothes line being easily and quickly wound thereon and readily 15 carried.

A further object of this invention is to provide a clothes line reel consisting of comparatively few parts that can be easily and quickly assembled, and manufactured at a 20 comparatively small cost, and used without injury to a clothes line.

I attain the above objects by a mechanical construction that will be hereinafter specifically described and then claimed, and reference will now be had to the drawing, wherein:—

Figure 1 is a side elevation of a reel partly broken away and partly in section, and Fig. 2 is an end view of a reel.

30 A reel in accordance with this invention comprises a spindle or cylindrical body 1 and secured to one end of said body by screws 2 or other fastening means is a circular stationary head 3. The screws 2 are 35 also employed for holding the inner end 4 of an angularly disposed crank 5 in engagement with the head 3. The crank 5 terminates in a handle 6, which facilitates revolving the spindle and the head 3 attached 40 thereto.

The reference numeral 7 denotes a circular head corresponding in diameter to the head 3 and secured to the outer side of the head 7 by screws 8 or other fastening means 45 is a handle 9 by which the clothes line reel can be easily carried or held whereby the spindle 1 and the head 3 can be revolved relatively to the head 7. The head 7 is provided with a concentric opening 10 and 50 mounted in said opening is a bushing 11.

Secured to the sides of the head 7 and having openings registering with the bushing 11 are side plates 12, these plates being held in position by screws 13 or other fastening means. Extending through the plates 12 and the bushing 11 is a screw 14 that is 55 mounted in the end of the spindle or body 1 opposite the head 3. A smooth portion of the screw 14 permits of said screws revolving in the bushing 11 and to reduce the friction between the head 7 and the body 1 to a minimum, a small washer 15 is arranged upon the screw.

Connected to the body 1, adjacent to the head 7, by screws 16 or other fastening means is a resilient clip 17 and this clip is adapted to hold the inner end or first convolution of a clothes line wound upon the spindle or body 1. With the end of a clothes line attached to the spindle or body 1, it is 65 apparent that the handle 9 can be held in one hand while the body 1 and the head 3 are revolved through the medium of the other hand gripping the handle 6 of the crank 5. In this manner, a clothes line can 70 75 be easily and quickly wound upon the spindle or cylindrical body.

One embodiment of my invention has been illustrated, but it is to be understood that the structural elements are susceptible to 80 such changes, as in the size, shape, and manner of assemblage as fall within the scope of the appended claim.

What I claim is:—

A clothes line reel comprising a cylindrical body, a head, a crank, means for fixedly securing the crank, head and one end of the body together, a headed screw secured to and projecting from the other end of said body, a circular head, a bushing carried by 85 the last mentioned head and rotatably mounted upon said screw, means for maintaining the bushing in position, and a handle carried by the last mentioned head. 90

In testimony whereof I affix my signature in the presence of two witnesses. 95

JOSEPH J. BUSER.
